CATHODE RAY TUBE SYSTEM

Hugh C. Ressler, New York, N. Y., assignor to
Radio Inventions, Inc., New York, N. Y., a cor-
poration of New York

Application June 1, 1936, Serial No. 82,693

11 Claims. (Cl. 256—27)

This invention relates to cathode ray tubes. More particularly it relates to such tubes of the types commonly employed in the cathode ray oscilloscope.

5 My invention deals particularly with means and methods for focusing a stream of electrons upon the screen of a cathode ray tube, and for deflecting the so-focused stream in order to trace some particular pattern upon the screen such as 10 the reproduction of an image transmitted by television, or the reproduction of geometric figures for purposes of electrical analysis.

Cathode ray tubes, as hitherto constructed, have been unable to secure at the same time a 15 high degree of sensitivity and a high velocity of the electron stream impinging upon the screen. By the term "sensitivity", I refer to the displacement or deflection of the electron stream to a comparatively great extent, by the use of a relatively low deflecting voltage applied to electrostatic plates. The high velocity of the electron stream when it impinges upon the screen is desirable in order that a high degree of luminosity 20 may be produced by such impingement.

25 Furthermore, cathode ray tubes have encountered great difficulty because of certain irregular deflection effects, giving rise to an irregular or distorted curve or other figure upon the screen. Such irregularities in reproduction have been especially harmful when it has been desired to 30 reproduce a television image.

In the type of cathode ray tube employed with electrostatic deflection to produce a two dimensional image upon the screen, the distortion effects which have been found especially troublesome have been the effects which gave rise to an image of the so-called keystone type. By this type of distortion, is meant the lengthening of such an image either in its vertical or its horizontal dimension, at one side only. That is to say, a figure which should be truly rectangular, has one side lengthened with respect to the corresponding opposite side, so that obtuse angles appear on one side of the figure and acute angles 45 on the corresponding opposite side of the figure.

The reasons for the distortion effects above described have been obscure and not well-known in the art, but I have discovered the underlying reasons for certain of these distortion effects and 50 have devised an apparatus and a method of operating the same which will to a very great degree, or even completely, overcome these distortion effects.

One purpose of my invention is to produce a 55 cathode ray tube in which the electron stream can be subjected to the action of a deflecting field while the velocity of the stream is comparatively low, thus securing a high degree of sensitivity.

Another object of my invention is to construct 60 a cathode ray tube whereby the electron stream

may be deflected while of low velocity and may be accelerated after such deflection, in order to secure a brilliant screen spot.

Yet another purpose of this invention is to accelerate an electron stream whose direction of motion is subject to deflection, and yet have such acceleration act upon the electron stream so that its initial direction of motion after deflection will not be altered by the accelerating forces afterward applied to the stream. 10

A still further object of my invention is to provide electrostatic field producing, or screening means located between deflecting systems, so that the deflecting action of the second system will be substantially independent of the deflecting action 15 of the preceding system.

Another purpose of this invention is to provide means for securing in a cathode ray tube, electrostatic fields of radial nature, whereby electrons having different radial paths from a common 20 center will encounter an accelerating field of uniform or varying intensity but invariably directed substantially along said radial paths, and thus will be accelerated without change of direction.

Still another object of my invention is to provide a plurality of deflecting systems acting upon a single electron stream, where the second and subsequent deflecting systems are so constructed that the electron stream passing through the complex deflecting system will be subject to deflecting and/or accelerating fields of such character that the angular deflection caused by the first elements of the deflecting system will remain unchanged despite the transverse or other deflection caused by later deflecting elements. 25

Another object of this invention is to combine in a single cathode ray tube the qualities of high deflection sensitivity and high luminosity. 30

A still further purpose of this invention is to provide a cathode ray tube whose screen displays 40 a two-dimensional image, wherein the displayed image will be substantially free from distortion due to the keystone effect.

I have illustrated the principles involved in my invention and certain embodiments thereof in the 45 accompanying drawing where

Fig. 1 represents schematically a portion of the interior of a cathode ray tube.

Fig. 2 shows in detail a pair of accelerating 50 anodes as used in the system of Fig. 1.

Fig. 3 illustrates a conventional tube system shown in order to illustrate the keystone effect.

Fig. 4 illustrates diagrammatically the appearance of images upon the screen of a cathode ray tube, illustrating the production of the keystone 55 effect.

Fig. 5 represents schematically a simplified form of my invention as applied to a cathode ray oscilloscope tube. 60

Fig. 6 illustrates diagrammatically the electrostatic fields of the system of Fig. 5.

Fig. 7 illustrates yet another modification, wherein a special form of deflecting plate is employed.

Referring now to Fig. 1, the cathode 10 is shown enclosed in a shielding element 11, with which it cooperates to form the so-called electron gun. Elements 12 and 13 are metal plates provided with slots 14 and 15 respectively, through which the electron stream passes in order to secure a proper definition thereof, and for other purposes as set forth in copending application Serial Number 738,220 filed August 3rd, 1934.

In this application the production of an electron stream of a desired cross section, direction of motion, and whose component electrons have a substantially uniform velocity is disclosed, but it is to be understood that this present invention may be used in connection with any other method of securing an electron stream having approximately these characteristics. While it is desirable that electron stream have the qualities just described yet this present invention will function, even if to a less perfect degree, upon electron streams which do not possess precisely the qualities just enumerated.

The electron stream emerging from the apertures 14 and 15 is denoted by reference numeral 16 and this stream then passes through an aperture 17 in an anode structure 18, which may be in the form of a metal plate, disc or other suitable shape.

At 19 and 20 I have shown two deflecting plates of the electrostatic type, producing a substantially uniform electrostatic field therebetween. Located beyond deflecting plates 19 and 20, lies another anode 21 in the form of a cylindrical metal plate (see Fig. 2).

Beyond plate 21 lies still another anode 22, also in the form of a cylindrical plate. Plates 21 and 22 are provided respectively with elongated slots 23 and 24 extending in a direction at right angles to slots 14 and 15, through which the electron stream can readily pass after being deflected substantially only in one direction. The electron stream 16, after passage through deflection system 19, 20 has its direction of motion altered according to the relative electrostatic charges upon the respective plates of this system, and I have illustrated by means of a series of lines 25, 25 the varied direction of motion which this stream may assume. It is to be understood that at any one instant, the electron stream can only occupy the position shown by a single one of these lines.

While I have shown plates 19 and 20 as being parallel it is to be understood that they may be obliquely disposed, relatively to each other, as well known in the art.

The anode 21 is electrically connected with the anode 18, so that the electron stream is not substantially accelerated in its passage through deflection system 19, 20. Anode 22 has applied to it an accelerating potential, with respect to anode 21, so that the electron stream which has passed through slot 23 will be accelerated during its passage between this slot and slot 24 in anode 22. It is well known in the art that by the proper design of plates 19 and 20, the electron stream which has been acted upon by these plates so as sequentially to occupy the various lines of direction, as indicated at 25, may be considered always to emanate from a fixed point 26, located in the space between these deflecting plates. In

other words, point 26 may be looked upon as the virtual common center of origin of the variously deflected electron streams coming from deflection system 19, 20. Since plates 21 and 22 produce therebetween a radial field centered at the point 26, it will be seen that electrons entering slot 23, provided that they always come from a single central source 26, will encounter between plates 21 and 22 a uniform radial field of traverse, so that the acceleration of these electrons will be accomplished without any change in their direction of motion due to the fact that such motion and such accelerating field are both identical in direction.

It can be seen that the particular system just illustrated and described is suited for acting upon an electron stream which has motion in one dimension only.

However, unless the accelerating field between anodes 21 and 22 is made of too high a value, the rays passing through slot 24 may then be further deflected in a dimension at right angles to the dimension in which deflecting system 19, 20 has already caused them to be deflected. Thus, by dividing the accelerating action into two stages, it is possible to construct a cathode ray tube according to this invention, which shall be operative to give two dimensional scanning.

It is to be understood that the principles of this invention are equally operative with deflecting elements which produce a substantially uniform and concentrated magnetic field and since the equivalency of these two types of deflecting structures is well known in the art, it is thought unnecessary to explain the operation of my invention in detail, when a magnetic deflecting field is employed.

My system provides a short path of traverse for the electron stream, permitting the use of low velocity and yet affording a comparatively high sensitivity of deflection. At the same time it minimizes the shielding and shadowing difficulties which present themselves when a low velocity electron stream has a long traverse path, or when the path between the deflecting system and the screen is not free of obstructions.

Referring now to Fig. 3 I have here shown a deflecting system of the conventional type employed in two-dimensional cathode ray tubes. A pair of deflecting plates 29 and 30 deflect the stream in one dimension and as previously explained this stream will seem to originate from a virtual central point 31 located between these plates. After leaving these plates, the electron stream then passes through another pair of plates 32 and 33 which are perpendicular to the first set and which deflect the beam in the other dimension. If both these sets of plates are independent from one another and if the relative potential of each plate of a given set is simultaneously equal in degree, but of opposite sign with respect to the anode of the electron system, then the two sets of plates will theoretically function independently of one another.

However, in actual practice, not only is it extremely difficult to keep each set of plates symmetrically charged with respect to the anode potential at a given instant, but also for reasons of practical construction and for minimizing the number of external connections necessary in a tube employing such a system, it is frequently desirable to connect one deflecting plate of each pair directly to the anode. Under such conditions, I have discovered that the second deflecting system not only will act to displace the elec-

tron beam in the desired direction, but in addition it will affect the velocity of the electron stream, due to the fact that the mean instantaneous potential of the deflecting plates will be finite and either positive or negative with respect to the potential of the anode proper, and not zero as desired.

In Fig. 3 I have illustrated by the line OQ the path of a ray leaving deflecting system 29, 30, when the mean potential of the deflecting plates 32 and 33 is the potential of the anode proper, i. e., when no electrical signals are being applied to these last mentioned plates. If we now consider that plate 33, the insulated one of the pair 15 of plates 32, 33, has applied to it a voltage positive with respect to the anode voltage of the system, this positive voltage will cause the electron stream to assume the position denoted by the line OR, since the field thus established between plates 20 29, 30, and 32, 33, gives the beam a net acceleration in the forward direction, whereas the beam has a component of motion in two directions, due to its radial nature, as previously described.

It is to be understood that the motion of the stream within the rear plates is really a parabola, although it appears a straight line, due to its relatively slight curvature, and that the curvature between the rear and forward plates has been exaggerated, in order to more clearly display the 30 principles of my invention.

This change of direction of the beam takes place principally between the forward edges of plates 29, 30 and the rear edges of plates 32, 33, so that during this portion of its path of traverse, 35 the ray is curved concavely downward.

A similar analysis will show that a negative potential applied to insulated plate of the pair 32, 33 will decelerate the electron stream with respect to its forward motion, so that the line OP 40 will represent the line of direction of the stream under such conditions.

Considering now additionally Fig. 4, the point 40 represents the center of the pattern which the electron stream can place upon the screen. The lines XX and YY represent the conventional axes of a Cartesian system of coordinates. The lines 45 41, 42 and 43, 44 represent two lines parallel to the X axis of this system, and manifestly in reconstructing a television image for example, it is 50 desirable that all the horizontal elements of the picture take up positions which will correspond to such lines, with respect to their being parallel to the X axis. However, in the case of the system shown in Fig. 4, it will be evident that the 55 line 43, 44 which should be parallel to the X axis, will actually take up a position corresponding to the line 45, 46. The reason for this displacement, will be apparent when it is considered that the electron stream at the instant it is at the left 60 hand end of line 45, 46, will be subjected to a decelerating action of deflecting plates 32, 33, as just described in the discussion of Fig. 3, causing an increase in the vertical displacement of the spot.

At the right hand end of line 45, 46, the electron stream will be accelerated by the system 32, 33, thus causing a decrease in the net vertical displacement of the spot. This species of distortion just described is the so-called keystone effect.

Referring now to Fig. 5 I have there shown a radially shaped shield 50 provided with a longitudinal slot 51 and located between the first deflecting system 29, 30 and the second deflecting

system 32, 33. This plate 50 is connected to the anode of the system.

The shield 50 is a segment of a cylindrical surface, whose center is the point 31 located in deflecting system 29, 30. Since the deflected rays 5 leaving the plates 29, 30 are radial about point 31, and since the field shown by the dotted lines of Fig. 6 is also radial, these rays will suffer no displacement of direction for the reasons previously pointed out in connection with Figs. 1 and 2. 10

Referring now additionally to Fig. 6, I have here illustrated by dotted lines the electrostatic equipotential lines existing in the plane of the drawing and between the adjacent edges of the plates of the respective deflecting systems. It 15 will be noted that the interpositioning of plate 50 has caused the electrostatic field between the two sets of plates to assume a substantially radial form, thus allowing independent action of the two sets of plates and eliminating the keystone 20 effect just described.

While for purposes of clarity I have described shield 50 as centered about point 31, yet in practice I have found that it often is desirable to give this element a greater degree of curvature, to 25 compensate for any departure from the assumed radial path, such as may occur when the accelerating field is produced by a plane electrode.

The mode of construction shown in Fig. 5 thus 30 practically or completely eliminates the species of distortion giving rise to the keystone effect, since the direction of the ray is not altered when it passes from one set of deflecting plates to another.

While I have shown the pairs of deflecting 35 plates of dissimilar sizes, it is to be understood that they may be of the same size.

In Fig. 7 I have shown an alternative method of producing such a radial field between deflecting plates 29, 30 and a second set of deflecting 40 plates 53, and 54. In this case each plate, 53 and 54, has both of its curved edges in the shape of arcs approximately concentric with point of ray origin 31. Such a shape of plate will establish a substantially radial electrostatic 45 field between the two sets of plates.

I have found, however, that a still better result is had by making the curved edge nearest the point of ray origin at 31 a true circular arc centering on 31, and by making the curved edge more 50 distant from the origin according to a curve having a smaller average curvature. The optimum form for this more remote edge, when the plates 53 and 54 are used in conjunction with a substantially planar accelerating electrode, is determined by the polar equation:

$$R = R_0 + \frac{D}{\cos \theta}$$

where R is the distance from the point 31 to the more remote edge of the plate, R_0 is the uniform distance from the point 31 to the nearer edge of the plate, D is the distance between the nearer and more remote edges of the plate in the direction of the axis of the system, and θ is the angle measured from the axis of the system. 60

This mode of constructing the deflecting plates is more expensive, and such plates more difficult to correctly mount in a tube, than the simpler form shown in Figs. 3 to 6 inclusive, but is 65 advantageous in certain cases.

The fields of force shown in the various figures of my drawing are to be understood as illustrative and not as mathematically exact.

While I have shown and described certain em- 75

bodiments of my invention, yet it is to be understood that this invention is not limited to the specific forms herein shown, but merely to the extent of the claims hereunto appended. Furthermore it is to be understood that many variations of the forms here shown are possible without departing from the spirit of this invention.

I claim:

1. In a cathode ray tube, the method of securing distortionless projection of an electron stream which includes generating said stream, deflecting said stream, and passing the deflected stream through an electrical field whose accelerating action upon said deflected stream is always coincident in direction with the motion of said stream after deflection.

2. A cathode ray deflection and acceleration system including in the order specified, means for producing an electron stream, means for deflecting said stream, and means for accelerating the deflected stream, said last means producing a substantially radial electrostatic field about the virtual point of origin of said stream, located within said deflecting means.

3. A cathode ray tube system including a tube having an anode, two sets of deflecting plates at right angles to one another and a slitted electrostatic shield located between said two sets of plates and having a radius of curvature substantially about the virtual center of ray origin located within said first set of deflecting plates, said shield being connected to said anode and also including means for applying electrical energy to said deflecting plates.

4. In a cathode ray system, a tube having an anode and means for producing an electron stream, means for deflecting said stream in one direction about a virtual focal point of origin, slitted shielding means substantially concentric with said point of origin and connected to said anode, means located beyond said shielding means for deflecting said stream in another direction and means for applying electrical energy to said deflecting means.

5. A cathode ray tube system including a tube having a conducting slitted shield, located between two mutually perpendicular deflecting systems, and curved about a central point substantially coincident with the virtual point of cathode ray origin of the first deflecting system, and connected to the anode of the tube and including means for producing and projecting a cathode ray beam along said system of elements.

6. In a cathode ray tube system, a deflecting system comprising two conducting plates closely adjacent to one another and between which the cathode ray stream passes, said plates taking the form substantially of outer portions of segments of a circle whose center is substantially at the point of virtual origin of said cathode ray stream, the arc of said segment more remote from the centre being defined by the polar equation:

$$R = R_0 + \frac{D}{\cos \theta}$$

where, R is the distance from the point of ray origin to said arc, R₀ is the uniform distance

from said point of ray origin to the arc of the segment nearer the centre, D is the minimum distance between the nearer and the more remote arcs, and θ is the angle measured from the longitudinal axis of said deflecting system, and means for causing said cathode ray stream to pass between said plates, including connections to sources of electrical energy.

7. A cathode ray deflection and acceleration system including means for generating cathode rays, means for deflecting said rays so that they will have substantially a unique virtual point of origin, and means for accelerating the deflected rays, said last accelerating means comprising two spaced-apart cylindrical conducting sheets having slits therein and being curved about a center substantially coincident with said unique point of ray origin.

8. A cathode ray tube system including cathode ray accelerating apparatus for operation upon cathode rays having a common point of virtual origin, comprising two spaced-apart cylindrical conducting sheets curved about said common point of origin of said rays and also including means for generating said cathode rays and bringing them to said common point of virtual origin.

9. A cathode ray deflecting system including means for producing an electron stream, means for deflecting said stream in one plane so that said stream shall at all times have substantially a single virtual point of origin, means for deflecting said stream in another plane and corrective means positioned between said two deflecting means and comprising a slotted cylindrically-shaped conducting sheet whose radius of curvature is finite and greater than the radius of curvature centered about said virtual point of origin.

10. A cathode ray system including means for generating an electron stream, means receiving said stream and deflecting it substantially in one direction only, and means for accelerating said stream after it has been deflected, said last means comprising means for producing about the point of virtual origin of said stream, located within said deflecting means, an electrostatic field substantially radial in character whose accelerating action upon said deflected stream is substantially coincident in direction with the direction of motion of said stream after deflection, said accelerating means exerting substantially no deflecting action upon said stream.

11. A cathode ray system comprising means for generating an electron stream, means for deflecting said stream, means for generating an electrostatic field exerting a force upon the electron stream substantially along the direction of its motion, said stream after deflection passing through said field, the accelerating action upon the deflected stream being such that the direction of linear motion of the stream upon entering and passing through the field remains substantially the same and the projection of the stream is substantially undistorted.

HUGH C. RESSLER.
